CANISTER FOR SUGAR

Michael Saphier, New York, N.Y., assignor to Lincoln Metal Products Corporation, Brooklyn, N.Y., a corporation

Filed Feb. 12, 1962, Ser. No. 68,772

Term of patent 14 years

(Cl. D44—6)

The FIGURE is a perspective view of a canister for sugar showing my new design, the essential features thereof being shown in full lines.

I claim:

The ornamental design for a canister for sugar, substantially as shown and described.
